UNITED STATES PATENT OFFICE

HENRY H. WHEELER, OF BROOKLYN, NEW YORK, ASSIGNOR TO INTERNATIONAL CIGAR MACHINERY COMPANY, A CORPORATION OF NEW JERSEY

CIGAR-BANDING MACHINE

Application filed July 17, 1928. Serial No. 293,365.

This invention relates to cigar banding machines of the type designed to receive cigars and carry them past a device for wrapping bands around same and then eject same, automatically and rapidly. This machine is intended for use with a suitable automatic cigar feed, such as that described in my co-pending application S. N. 268,434, filed April 9, 1928.

One of the principal objects of the present invention is to produce such a machine which will eject the cigars after banding with the same side up as received, in order that the cigars may be repacked in the same position as originally packed in the cigar box. This is important because cigars are often banded after boxing, and being relatively brittle after remaining in boxes for a while, unless they are repacked in their original positions, they will not go into the box without forcing, which is liable to injure the cigars. Another object of the invention is to provide a simple and compact turret and clamp structure for such a machine by which the cigars may be rotated as the turret revolves to maintain the same side of the cigar uppermost throughout its travel on the turret. Still another object of the invention is to provide improved means for wrapping the bands smoothly and tightly about the cigar, despite variations in the thickness and shape of the band and in the size of the cigar. Another object of the invention is to provide a simple and direct transfer device for transferring bands from a magazine to the banding device. With these and other objects not specifically mentioned in view, the invention consists of certain constructions and combinations which will be hereinafter fully described and then specifically set forth in the appended claims.

In the general operation of the machine selected to illustrate the invention, the cigars from the automatic cigar feed are received one by one into the jaws of the clamps on an intermittently revolving turret which carry them into position below a band applying mechanism composed of a band magazine in which the gummed bands are

stacked, of a transfer arm which pulls out one band at a time from the magazine and, after passing its gummed end over a moistening drum, delivers it to the band folder which, in turn, takes it to and wraps it around the cigar held in the turret. Both the transfer arm and the band folder are provided with suction heads for holding the band, the suction being switched from the transfer arm to the carrier of the folder 55 at the moment of delivery. After the band is applied, the turret at its next step takes the banded cigar to the ejecting station, at which it is taken from the turret and placed on the delivery table, on which the cigars 60 arrive in the same order and with the same side up as when originally taken from their box, the turret jaws being provided with planetary gears, coupled with a stationary sun gear, which cause them to partake of the 65 rotative motion of the turret.

In the accompanying drawings which form a part of this specification and in which like characters of reference indicate the same or like parts:

Fig. 1 is a side elevation, partly broken away, of the improved banding machine;

Fig. 2 is a front elevation of the same, seen from line 2-2 of Fig. 1, and shown partly in cross section;

Fig. 3 is a fragmentary side elevation showing the band moistener, seen from line 3-3 of Fig. 1;

Fig. 4 is a fragmentary top view showing the band applying device; and

Figs. 5 to 8 are diagrammatic views showing the band applying device in the successive stages of its operation.

In carrying the invention into effect, there is provided an intermittently rotating turret, a series of clamps projecting from a side of said turret arranged to support cigars perpendicular to the plane of rotation of the turret so that a substantial portion of the cigar extends beyond said clamps, 95 together with suitable means for successively banding the extending parts of the cigars and means for operating the clamps to receive and deliver the cigars respectively prior to and after banding. In the best 100

constructions, means are also provided for rotating the clamps with respect to the turret to maintain the same side of each cigar up throughout its travel on the turret. 5 Preferably the banding means will include a flexible enwrapping member. The best constructions will also include means for transferring bands from a band magazine to a banding device comprising a swinging 10 arm, a lever pivoted on said arm, a suction head on one end of said lever arranged to coact with the band in said magazine, a stationary cam acting on the lever to guide the band on said head into the range of 15 action of said device, on swinging of the arm. The means above described may be widely varied in construction within the scope of the claims, for the particular machine selected to illustrate the invention is 20 but one of many possible embodiments of the same. The invention, therefore, is not to be restricted to the specific construction shown and described.

Referring to Figs. 1 and 2, the framework 25 of the machine consists of two end frames 10 and 11, joined on top by a frame 12 and at the bottom by a tie frame 13, by which it is fastened to the sub-structure 14. The end frames 10 and 11 support the turret shaft, drive shaft, transmission shafts, cam shafts and fulcrum shafts, and the top frame 12 carries the band applying mechanism, band magazine, transfer lever, moistener and suction control.

35 Power from a belt 15 is transmitted to a clutch pulley 16 on a drive shaft 17 which has a pinion 18 in mesh with a gear 19, which is loose on a stud 20 and turns a pinion 21 attached to it. The pinion 21, in turn, drives a gear 22 on a shaft 23. The gear 22 meshes with a gear 24 on a cam shaft 25 which, by means of a pinion 26, drives a gear 27 on a cam shaft 28. On the end of the cam shaft 23 is mounted 40 a disc 29, the hub of which has an arm 30 carrying a driving roller 31, which turns a Geneva stop wheel 32 mounted on stud 33, the disc 29 being suitably cut away to form the lock for the geneva 32. Attached to the 45 geneva, and turning with it, is a spur gear 34 in mesh with a gear 35 which drives a turret shaft 36 in a step-by-step motion in accordance with the steps of the Geneva stop 32.

55 The cigars to be banded are preferably fed to the cigar holding clamps on the turret by the feed mechanism described in the application above referred to, which feeds the contents of a cigar box layer by layer. 60 However, the cigars may be fed by other means or by hand. The said feed mechanism is operated by rods 37 and 38 controlled by cam levers 39 and 40 fulcrumed on a shaft 41 and having the rollers 42 and 65 43 in engagement with cams 44 and 45, re-

spectively. The conveyor 46 of the cigar feed, whose sprocket 47 on shaft 48 is driven, through suitable means such as the ratchet and pawl disclosed in the above mentioned co-pending application, by a 70 crank 49 through a rod 50 controlled by a lever 51 on a shaft 52, which is rocked by a cam lever 53 having a roller 54 in engagement with a cam 55 on the shaft 25, advances the cigars, one layer at a time, towards the banding machine turret 56 for 75 delivery one by one into the cigar holders on said turret, by any suitable transfer means such as that disclosed in the above application.

The disk shaped turret 56 is mounted on a shaft 36 and carries perpendicularly projecting from the side of the turret a number of equally spaced cigar holders, each composed of a rigid lower jaw 57 and a 80 pivoted upper jaw 58, arranged to support cigars perpendicular to the plane of revolution of the turret. The lower jaws 57 have recessed hollow studs 59 which pass through and are rotatably mounted on turret 56, the 85 cigars being supported coaxially within these studs. These studs are rotated from the movement of the turret by a planetary gear system consisting of the planet gears 60 fixed to the studs and meshing with intermediate gears 61 on studs 62 mounted on turret 56, the gears 61 in turn meshing with a stationary sun gear 63 on a sleeve 64 which is clamped to the end frame 10 by a nut 65 and which carries the bearing sleeves 100 for the turret shaft 36. The gears 60 and 63, being made of the same diameter, the 105 holders 57 on the forward rotation of the turret are turned back by an equal annular amount so that the cigars held in them remain in the same relative position and are carried around the turret in a parallel motion and the side that was uppermost when the cigar was received remains uppermost throughout the travel of the cigar on the 110 turret. The upper jaws 58 of the holders are pinned to the horizontally disposed long arms of bell crank levers 66, the flat axially extending end surfaces of which bear upon flat springs 67 attached to the jaws, thereby 115 holding the jaws 58 in their horizontal position and still giving them sufficient resiliency to accommodate themselves to variations in the position and shapes of the 120 cigars.

To open and close the jaws 58, the bell crank levers 66 are pivoted in the lugs 68 on the base forming part of the lower jaws 57 and their vertically projecting short arms are pinned to rods 69 which pass through the studs 59 and whose heads fit into recesses of said studs and project from the end of the turret. In the recesses of studs 59 are placed coil springs 70 which bear against the shoulders of the heads of the rods 69

and hold the jaws 58 in their closed position. At the time when a banded cigar is ready to be removed from one holder of the turret and a new cigar is being delivered into the 5 diametrically opposite holder, levers 71, fast on a shaft 72 in bearing brackets 73, are turned by an arm 74 attached to a rod 75 actuated by a cam lever 76 fulcrumed on a shaft 77 and having a roller 78 in engagement with a cam 79 on the shaft 23, thereby pushing against the resiliently held rods 69 which thus open the jaws 58 of these two 10 holders long enough to receive or deliver a cigar.

15 Upon each cigar holder, bearing against the inside face of the turret disk 56, there is slidably mounted a hollow rectangular frame 80 (Fig. 2), which on its flanged lower edge carries an axially projecting flat 20 spring 81, the free end of which extends beyond the holder jaws to the point on the cigar at which the band is to be applied. The frames 80 are drawn upwards by springs 82 fastened to the pivot pins in lugs 68, 25 so that normally the ends of springs 81 bear against the undersides of the cigars carried in the holders. When a band is being applied in the uppermost position of the turret, a roller 83 at the end of a lever 84 30 fulcrumed on a stud 85 in lugs 86 of the top frame 12 and actuated by a rod 87 controlled by a cam lever 88, on a shaft 89, having a roller 90 in engagement with a cam 91 on a shaft 25, pushes down on the 35 frame 80, thereby holding the spring 81 clear of the cigar and permitting the band to be folded around it, the spring 81 on its return to normal position closing up and sealing the overlapping ends of the band.

40 The band applying mechanism (Figs. 1 to 4) is mounted on the top frame 12. The band magazine consists of two vertical end frames 92 connected by the right and left threaded horizontal screw 93 which is held 45 in the block 94 and by which their distance can be adjusted to the length of the band B to be used. Each end frame has a loose side plate 95 hinged on a threaded pin 96 enabling the magazine to be adjusted to 50 different widths of bands to which it is set by the nuts 97 on the threaded ends of pins 96. In Fig. 4, one of these side plates is shown in opened position by dotted lines.

55 The bands which are placed in the magazine with the gummed side down, are taken out from the bottom of the stack one by one, as each cigar arrives in the top position on the turret, by the transfer lever 98, provided at one end with a suction head 98^a, which 60 holds them by suction and carries them into position to be folded around the cigar, leaving each band suspended from the suction head hereinafter described, of a carrier 99 of the banding device before going back 65 for the next. For this purpose, both the

suction head 98^a and the band carrier 99 are connected, by flexible tubes 100 and 101 respectively, with a suction valve 102 attached to the frame 12, this valve having a plunger 103 attached to an arm 104 on a shaft 105 which is supported in the frame 12 and is actuated by an arm 106 which, through a rod 107 and a cam lever 108 loosely mounted on a shaft 109, is controlled by a roller 110 engaging the cam 90 on the shaft 23. The plunger 103 switches the suction of a tube 111, which is connected to a suction pump or other exhaust means, from tube 100 to 101 and back at the moment when arm 98 holds the band.

70 The transfer lever 98 is clamped to a stud 112 journalled in an arm 113 on a shaft 114 and has an extension 115 carrying a roller 116, which engages the track of a stationary cam 117 mounted on the frame 12. The shaft 114 has a fixed arm 118 which is connected by a rod 119 with an arm 120 on the shaft 109, the motion of which is controlled by a cam 121 on the shaft 23 through a lever 122 having a roller 123, thus causing the transfer arm 98 to move into the dotted position shown in Fig. 2, with the band in a horizontal plane above the cigar parallel to its plane in the magazine.

75 On its way into this position, the gummed end of the band carried by the transfer lever wipes over the drum 124 of a moistener 125, shown in Figs. 1, 3 and 4, which is slidably attached to a bracket 126 affixed 80 to a frame 12 and secured in place by a thumb screw 127 so that, by loosening the latter, it can be readily removed for cleaning. The bracket 126 carries a stud 128 on 85 which is mounted a bevel gear 129 meshing with a bevel gear 130 on the shaft of drum 124, and which is connected by a lever 131 and a link 132 to a lug 133 of a reciprocating slide 134, thereby turning the 90 drum 124. The lever 131 engages with a 100 stud 128 through a number of rollers confined in inclined pockets of its hub, so that the drum 124 can turn in one direction only, standing still when the lever moves back 105 in the opposite direction and thus partakes 110 in a step-by-step forward motion presenting 115 a new moistening surface to each succeeding band.

When the band B has been delivered into 120 folding position, above the cigar C in the turret, it is held by the suction of the carrier 99 against the flexible enwrapping member 135, which is perforated at its center to allow passage of air and which is stretched across folding fingers 136 by 125 springs 137 attached to pins 138 in a slide 134. The folding fingers 136, which are provided with rollers at their bends and at their free ends for the flexible member 135 to rest on, are pivoted on studs 139 in 130

the slide 134 and are held in tension by a spring 140 hooked across their upper ends which extend beyond the pivots. In a lug, projecting inwardly from its pivot, each finger carries an adjustable stop screw 141, one of which is set in advance of the other, so that when the fingers are carried downwards by the slide 134, the longer screw comes into engagement with the stop 142 attached to bracket 143 on the under side of frame 12 before the shorter screw is arrested by the same. The slide 134, by means of a link 144, is attached to a lever 145 mounted on a shaft 146 in the frame 12, the said shaft carrying an arm 147 actuated by a rod 148 connected to a cam lever 149 on the shaft 89, having a roller 150 in engagement with cam 151 on the shaft 25.

The operation of the banding device is shown in Figs. 5 to 8. The band B, having been brought to the folding fingers while the slide 134 is held up by the downward pull of rod 148 (Fig. 5), the transfer arm 98 returns to its position with suction head 98^a under the bottom band of the magazine, shown in Fig. 2, and the rod 148 ascends, causing the slide 134 to move downwards over the cigar C, thereby causing the flexible member 135 to enwrap the cigar, folding the band B tightly and smoothly over the top and down the sides of the same, as shown in Fig. 6. Having arrived in the position shown in the latter figure, the longer of the stop screws 141 is just being engaged by the stop 142 so that upon the further down movement of the slide 134, the corresponding finger 136 now moves inward, thereby causing one end of the band B to be folded over the under side 40 of the cigar C, as seen in Fig. 7, which shows the position in which the shorter of the screws 141 is coming into contact with the stop plate 142. Thereafter, upon the continuation of the downward motion, both 45 fingers move inward towards each other and complete the folding of the band entirely around the cigar, whereupon the spring 81 which has thus far been held away from the cigar by rod 87 and lever 50 84 to permit the folding movement of the band, is brought up by the springs 82 and presses the ends of the band together, as shown in Fig. 8. The gum on the end of the band, having been moistened when passing over drum 124 while being transferred by arm 98, the upward pressure of spring 81 seals the band upon the cigar and the spring remaining in its up-position until the cigar is discharged from the turret, 60 holds it closed until dry.

The stop plate 142 for the finger controlling stop screws 141 also forms the lower guide for the carrier 99, the upper guide 152 being attached to the top of frame 12. A 65 stop 153 is provided on carrier 99, which

comes to rest on guide 152, as shown in Fig. 7, at the moment when the band comes in contact with the cigar, that is, in a position of the slide 134 a part of the way down between the positions shown in Figs. 5 and 6. It remains in this position during the entire folding operation, its object being to prevent the weight of the carrier from resting on the cigar and thereby causing damage to the same. A weak coil spring 154 placed around the carrier below the fixed collar 155 keeps the carrier in tension in its up position, so that its suction head 156 bears against the lower guide plate 142 when the transfer arm 98 delivers a band to the same.

To prevent damage to the cigar from pressure on its unsupported end while the band is being applied, the head of the cigar C is supported by an arm 157 pivoted in the frame 11 and connected by a rod 158 with a lever 159 clamped to a shaft 77 which, as previously described, is actuated through the cam lever 76 by cam 79.

The banded cigar is ejected from the turret upon its arrival at the delivery station which is located at the horizontal center line of the turret, diametrically opposite to the loading station. At this point, there is a reciprocating slide 160, held in guides attached to the under side of delivery table 161 and set in motion by having its rack portion 160^a in engagement with a gear segment 162, fulcrumed on the shaft 77 and having an arm 163 controlled through a roller 164 from a cam 165 on the shaft 23. To the slide 160 is attached an angle piece 166 which, by each backward stroke of the slide, is brought in a position behind the descending cigar holder of the turret, so that the next forward stroke of the slide will, on the release of the holding jaw by lever 71, move forward (to the right as shown in Fig. 1) between the jaws and thus eject the cigar from the turret.

The cigars having been kept top up by the holder planet gears while going through the turret, they will be in the same position when finally delivered on table 161 as they were placed on the feed conveyor 46, and can therefore be replaced in their original position into the box from which they were taken.

What is claimed is:

1. In a cigar banding machine in combination, an intermittently rotating turret, a series of clamps projecting from a side of said turret and arranged to support cigars perpendicular to the plane of rotation thereof and with a substantial portion of the cigar extending beyond said clamps, separate means for successively banding said extending parts of the cigars, and means for operating said clamps to receive and deliver the cigars respectively before and after banding.

2. In a cigar banding machine in combination, an intermittently rotating turret, a series of clamps projecting from a side of said turret and arranged to support cigars perpendicular to the plane of rotation thereof and with a substantial portion of the cigar extending beyond said clamps, separate means for successively banding said extending parts of the cigars, means for operating said clamps to receive and deliver the cigars respectively before and after banding, and means cooperating with the clamps to cause the same to deliver the cigars with the same side up as when received. 5
3. In a cigar banding machine in combination, an intermittently rotating turret, a series of clamps projecting from a side of said turret and arranged to support cigars perpendicular to the plane of rotation thereof and with a substantial portion of the cigar extending beyond said clamps, means for successively banding said extending parts of the cigars, means for operating said clamps to receive and deliver the cigars 10 respectively before and after banding, and means for rotating said clamps with respect to the turret to maintain the same side of the cigars up throughout its travel on the turret. 15
4. In a cigar banding machine in combination, an intermittently rotating turret, a series of clamps projecting from a side of said turret and arranged to support cigars perpendicular to the plane of rotation thereof and with a substantial portion of the cigar extending beyond said clamps, separate means for successively banding said extending parts of the cigars, and means for operating said clamps to receive and deliver the 20 cigars respectively before and after banding, said banding means including a flexible enwrapping member. 25
5. In a cigar banding machine in combination, an intermittently rotating turret, a series of clamps projecting from a side of said turret and arranged to support cigars perpendicular to the plane of rotation thereof and with a substantial portion of the cigar extending beyond said clamps, means for successively banding said extending parts of the cigars, and means for operating said clamps to receive and deliver the 30 cigars respectively before and after banding, said banding means including means for supporting the extending end of said cigar during the banding operation. 35
6. In a cigar banding machine in combination, an intermittently rotating turret, a series of clamps on said turret for supporting cigars, means for successively banding said cigars, means for operating said clamps to receive and deliver cigars respectively before and after said banding and means 40 for rotating said clamps to maintain the same side of said cigars up throughout their travel on the turret, said banding means including a flexible enwrapping member. 45
7. In a cigar banding machine in combination, an intermittently rotating turret, a series of clamps on said turret for supporting cigars, means for successively banding said cigars, means for operating said clamps to receive and deliver cigars respectively before and after said banding and means for rotating said clamps to maintain the same side of said cigars up throughout their travel on the turret, said banding means including a flexible enwrapping member. 50
8. In a cigar banding machine in combination, an intermittently rotating turret, a series of clamps on said turret for supporting cigars, means for successively banding said cigars, means for operating said clamps to receive and deliver cigars respectively before and after said banding and means for rotating said clamps to maintain the same side of said cigars up throughout their travel on the turret, said rotating means including a planetary gear system operated by the rotation of said turret. 55
9. In a cigar banding machine in combination, an intermittently rotating turret, a series of clamps on said turret for supporting cigars, means for successively banding said cigars, means for operating said clamps to receive and deliver cigars respectively before and after said banding and means for rotating said clamps to maintain the same side of said cigars up throughout their travel on the turret, said rotating means including studs journaled in said turret, each stud being arranged to support a clamp with the cigar therein extending axially of the stud, and means for rotating said stud and said clamp. 60
10. A carrier for cigars comprising a pair of jaws for holding a cigar, a base for carrying said jaws, means supporting said base for rotation about the longitudinal axis of the cigar, a bell crank lever pivoted on said supporting means with an arm supporting one of said jaws for movement toward and away from the other jaw, and means acting on the other arm of said lever for operating said jaw. 65
11. A carrier for cigars comprising a pair of jaws for holding a cigar, a base for carrying said jaws, means supporting said base for rotation about the longitudinal axis of the cigar, a bell crank lever pivoted on said supporting means with an arm supporting one of said jaws for movement toward and away from the other jaw, and means acting on the other arm of said lever for operating said jaw, said jaw operating means including a plunger connected to said lever and extending axially through said support. 70
12. Means for transferring bands from a magazine to a banding device comprising a swinging arm, a lever pivoted on said arm, 75

a suction head on one end of said lever arranged to coact with a band in said magazine, a stationary cam acting on the lever to guide a band on said head into the range of action of said device, on swinging of the arm.

13. Means for transferring bands from a magazine to a banding device comprising a swinging arm, a lever pivoted on said arm, a suction head on one end of said lever arranged to coact with a band in said magazine, a stationary cam acting on the lever to guide a band on said head into the range of action of said device, on swinging of the arm, said cam and lever cooperating to cause the head to receive and deliver the bands in parallel planes.

In testimony whereof, I have signed my name to this specification.
